UNITED STATES PATENT OFFICE.

PATRICK H. PENDERGAST, OF SYRACUSE, NEW YORK.

DESIGN FOR A BATH-TUB.

SPECIFICATION forming part of Design No. 35,304, dated November 19, 1901.

Application filed October 28, 1901. Serial No. 80,348. Term of patent 7 years.

To all whom it may concern:

Be it known that I, PATRICK H. PENDERGAST, a citizen of the United States, and a resident of the city of Syracuse, county of Onondaga, and State of New York, have invented and produced a new and original Design for Bath-Tubs, of which the following is a clear and exact specification, reference being had to the accompanying drawings, in which—

10 Figure 1 is a perspective view of a bath-tub, showing my new design. Figs. 2 and 3 are respectively longitudinal and transverse vertical sectional views through the bath-tub seen in Fig. 1.

15 The essential or material feature of my design consists of the elongated substantially rectangular receptacle, as seen in Fig. 1, having the slightly concavo-convex bottom wall 1, the substantially vertical side and end walls 2 and 3, the short curve corners at the junctions of the side, end, and bottom walls,

as seen in Figs. 2 and 3, the bottom wall having a gentle upward slope from substantially its central portion or apex to the side and end walls, and one of the side walls having the 25 intermediate shelves or ledges 4 and 5 disposed in planes one above the other and each having a center panel, the bottom wall also having the depending feet 6 and the shelf or ledge having the suspended legs 7. 30

Having thus described my invention, what I claim, and desire to secure by Letters Patent, is—

The design for a bath-tub as herein shown and described. 35

In witness whereof I have hereunto set my hand this 14th day of October, 1901.

PATRICK H. PENDERGAST.
